UNITED STATES PATENT OFFICE.

ANNA MARIE SHIPMAN, OF EAST ORANGE, NEW JERSEY, ASSIGNOR TO SUPREME COUNCIL ORDER OF THE AMARANTH, OF BROOKLYN, NEW YORK.

DESIGN FOR A FRATERNAL EMBLEM.

46,916.

Specification for Design.

Patented Feb. 2, 1915.

Application filed November 3, 1914. Serial No. 870,161. Term of patent 14 years.

To all whom it may concern:

Be it known that I, ANNA MARIE SHIPMAN, a citizen of the United States, and resident of the town of East Orange, county of Essex, State of New Jersey, have invented a new, original, and ornamental Design for a Fraternal Emblem, of which the following is a specification, reference being had to the accompanying drawing, forming part thereof.

The figure is a plan view of my design showing a fraternal emblem.

I claim:

The ornamental design for a fraternal emblem as shown.

ANNA MARIE SHIPMAN.

Witnesses:

MERVIN S. NEAR,
ARTHUR PHELPS MARR.
